UNITED STATES PATENT OFFICE

CARL H. HARRIS, OF BATTLE CREEK, MICHIGAN

TOOL OR IMPLEMENT FOR FEEDING PUNCH PRESSES AND THE LIKE

Application filed August 18, 1928. Serial No. 300,402.

The main objects of this invention are:

First, to provide an implement or tool for feeding punch presses and the like which is efficient in that it has a secure grip upon the work, is compact permitting the insertion of work in punch presses and the like having short strokes or which have a relatively narrow opening when the head is retracted.

Second, to provide an implement of the 10 class described which may be readily adapted for work of different character and machines of different types.

Third, to provide an implement of the class described in which the work may not only be 15 fed into the machine but may be discharged from the machine not only by means of the tool gripping the work but by a blast of air.

Fourth, to provide an implement of the class described utilizing air under pressure.

20 Objects relating to details and economies of my invention will appear from the description to follow. The invention is defined and pointed out in the claims.

A structure which is a preferred embodiment of my invention is illustrated in the accompanying drawing, in which:

Fig. 1 is a perspective view illustrating my improved implement grasping a sheet of metal.

30 Fig. 2 is a detail view partially in central longitudinal section.

As embodied in the structure illustrated in the accompanying drawing, my improved implement comprises a head member 1 having 35 a pistol-grip handpiece 2. This head member and the handpiece thereof have an inlet passage 3 for air under pressure, this passage being disposed longitudinally of the handpiece which is provided with a coupling 4 by 40 means of which an air hose may be attached.

The head member also has a vertical air discharge passage 5, the passages 3 and 5 being connected through the valve chamber 6. This valve chamber is in the form of a 45 bore disposed transversely of the passages and has a plug-like member 7 threaded therein and provided with a valve seat 8 for the ball valve 9. This valve is arranged to seat toward the passage 5, that is, so that the pressure of air acts to hold the valve on its seat.

A coiled spring 10 also acts to seat the valve, insuring its initial seating.

The member 7 has a passage 11 therein communicating through the passage 12 in the annular groove 121 with the passage 5. 55 This groove is provided so that it is not necessary to register the port or passage 12 with the passage 5.

The member 7 carries a valve actuating plunger 13 which projects to be engaged by the trigger-like lever 14 which is pivoted to the head member 15, the lever being thus positioned so that it may be conveniently grasped by the operator grasping the handpiece 2.

60 The exhaust nozzle 16 is preferably angled, as shown, and swiveled so that it may be swung in any desired direction. It should, however, direct the air away from the operator, but can also be used to blow finished work off the machine.

65 The suction cup 17 is preferably of flexible leather and is provided with a feather edge 18. This cup is mounted on the upper arm 19 which opens into the cup as shown and is connected through the coupling member 20 to the suction passage 21 in the head member opening to the passage 6.

70 The arm 19 is preferably a piece of copper tubing flanged at 22 and clamped to the coupling member 20 by means of the clamping sleeve 23. This provides a secure joint and permits changing the arms as may be desired, that is, arms of different lengths or shapes 75 may be substituted. Also, the arm 19 may be bent if desired, a further advantage in forming it of copper or other bendable material being that in the event it should be engaged by the dies, it is not likely to seriously injure the dies. Further, it may be easily adjusted

80 to the particular work, that is, should the work have an inclined surface for instance that it is desired to engage, the arm can be bent or adjusted to properly present the suction cup thereto. The work 24 illustrated is 85 a flat piece of sheet metal.

90 In use, the implement is connected to a source of air under pressure and when it is desired to pick up a piece of work, the suction cup is pressed down upon the same, opening 95 100

the valve permitting a blast of air to pass through the discharge passage 6 and this, owing to the connection with the suction cup, produces a suction or a partial vacuum in the suction cup. It will be understood that the suction continues as long as the valve is open. However, as soon as the valve is released, the suction is broken and the work released.

By proper direction of the nozzle, the blast of air may be effectively used to dislodge certain types of work from a machine such as a punch press. It will be understood that the exact timing or opening of the valve with the positioning of the suction cup on the work is not of importance except that if the valve be opened before the suction cup is pressed against the work there is a certain amount of air wasted.

By the aid of my improved implement or tool, work may be rapidly fed and removed from machines with safety to the operator and also to the machine. Experience has shown that its use increases production as the operators are relieved from anxiety or fear of being injured. Production can be increased also because the suction leather cup grasps the work more quickly than the hand in most cases, even on jobs not dangerous to the operator's hands.

Having thus described my invention, what I claim as new and desire to secure by Letters Patent, is:

1. An implement of the class described comprising a head member having a pistol-grip handpiece, an inlet passage disposed longitudinally of said handpiece, a vertical discharge passage and a suction passage opening to said discharge passage, a ball control valve for said discharge passage arranged so that the pressure acts to seat the same, a spring acting to seat said valve, a valve actuating plunger, a trigger-like valve actuating lever pivoted on said head member to coact with said plunger, a suction cup, and a tubular supporting arm for said suction cup adjustably mounted on said head member and connecting said suction cup with said suction passage.

2. An implement of the class described comprising a head member having a pistol-grip handpiece, an inlet passage disposed longitudinally of said handpiece, a vertical discharge passage and a suction passage opening to said discharge passage, a control valve for said discharge passage, a spring acting to seat said valve, a valve actuating plunger, a trigger-like lever pivoted on said head member, a suction cup, and a tubular supporting arm for said suction cup connecting said suction cup with said suction passage.

3. An implement of the class described comprising a head member having a pistol-grip handpiece, an inlet passage disposed longitudinally of said handpiece, a vertical discharge passage and a suction passage open-

ing to said discharge passage, a control valve for said discharge passage, a spring acting to seat said valve, a valve actuating plunger, a trigger-like valve actuating lever pivoted on said head member, a suction cup, a tubular angled supporting arm for said suction cup adjustably mounted on said head member and connecting said suction cup with said suction passage, and an angled exhaust nozzle for said discharge passage rotatably mounted on said head member.

4. An implement of the class described comprising a head member having a pistol-grip handpiece, an inlet passage disposed longitudinally of said handpiece, a vertical discharge passage and a suction passage opening to said discharge passage, a control valve for said discharge passage, a trigger-like valve actuating lever pivoted on said head member, a suction cup, a supporting arm for said suction cup having a passage therein connecting said suction cup with said suction passage, and an exhaust nozzle for said discharge passage adjustably mounted on said head member.

5. An implement of the class described comprising a head member having a pistol-grip handpiece, an inlet passage disposed longitudinally of said handpiece, a vertical discharge passage and a suction passage opening to said discharge passage, a control valve for said discharge passage, a trigger-like valve actuating lever pivoted on said head member, a suction cup, and a supporting arm for said suction cup having a passage therein connecting said suction cup with said suction passage.

6. An implement of the class described comprising a head member provided with a handpiece and having an inlet passage, a discharge passage and a suction passage opening to said discharge passage, a control valve for said discharge passage, a suction cup, a tubular angled supporting arm for said suction cup adjustably mounted on said head member and connecting said suction cup with said suction passage, and an angled exhaust nozzle for said suction passage rotatably mounted on said head member.

7. An implement of the class described comprising a head member provided with a handpiece and having an inlet passage, a discharge passage and a suction passage opening to said discharge passage, a control valve for said discharge passage, a suction cup, a tubular supporting arm for said suction cup connecting said suction cup with said suction passage, and an angled exhaust nozzle for said suction passage.

8. An implement of the class described comprising a head member provided with a handpiece and having an inlet passage, a discharge passage open to the atmosphere and a suction passage opening to said discharge passage, a control valve for said in-

let passage disposed in advance of said suction passage connection to said discharge passage, a suction cup, and a tubular angled supporting arm for said suction cup adjustably mounted on said head member and connecting said suction cup with said suction passage.

9. An implement of the class described comprising a head member provided with a handpiece and having an inlet passage for air under pressure, a discharge passage and a suction passage opening to said discharge passage whereby a suction is produced in said suction passage by the discharge of air under pressure through said discharge passage, a control valve for said discharge passage, a flexible suction cup, and a supporting arm for said suction cup having a passage therein connecting said suction cup with said suction passage.

10. An implement of the class described comprising a head member provided with a pistol-grip handpiece and having a passage therein for air under pressure exhausting to the atmosphere, a control valve for said passage, a trigger-like actuating lever for said valve, a suction cup, and a supporting arm for said cup having a passage opening within the cup and communicating with said air passage, said air passage having an exhaust nozzle adjustable to control the direction of the exhaust air.

11. An implement of the class described comprising a head member provided with a pistol-grip handpiece and having a passage therein for air under pressure exhausting to the atmosphere, a control valve for said passage, a trigger-like actuating lever for said valve, a suction cup, and a supporting arm for said cup having a passage opening within the cup and communicating with said air passage.

12. An implement of the class described comprising a head member provided with a handpiece and having a valve controlled passage for air under pressure exhausting to the atmosphere, a flexible suction cup provided with a feather edge, and a tubular bendable supporting arm for said cup opening thereto and connected to said head member so that the discharge of air under pressure through said air passage in said head will partially exhaust said suction cup.

13. An implement of the class described comprising a head member provided with a handpiece and having a valve controlled passage for air under pressure exhausting to the atmosphere, a flexible suction cup provided with a feather edge, and a tubular supporting arm for said cup opening thereto and connected to said head member so that the discharge of air under pressure through said air passage in said head member will partially exhaust said suction cup.

14. An implement of the class described

comprising a head member provided with a handpiece and having a valve controlled passage for air under pressure exhausting to the atmosphere, a flexible suction cup, and a tubular bendable supporting arm for said cup opening thereto and connected to said head member so that the discharge of air under pressure through said air passage in said head member will partially exhaust said suction cup.

15. An implement of the class described comprising a head member having a passage therein for air under pressure having a discharge open to the atmosphere, a control valve for said passage, and a suction cup mounted on said head member and connected with said air passage at the rear of said control valve.

In witness whereof I have hereunto set my hand.
